UNITED STATES PATENT OFFICE.

JOHN B. HUE, OF TARENTUM, PENNSYLVANIA.

DESIGN FOR A STAND.

Application filed October 17, 1923. Serial No. 7,524. Term of patent 14 years.

To all whom it may concern:

Be it known that I, JOHN B. HUE, a citizen of the United States, residing at Tarentum, in the county of Allegheny and State of Pennsylvania, have invented a new and original Design in a Stand, of which the following is a specification, reference being had to the accompanying drawing, forming a part thereof.

In the drawings:

The single figure of the drawing is a front elevation of a stand embodying my invention. The stand includes a suitable support

or base upon which is mounted a jardiniere, in combination with a rod or standard extending from the base and through the jardiniere, this standard supporting a fish bowl above the jardiniere and being provided at its upper end with an artistic bow which may be used for supporting a bird cage or other article.

What I claim is:

The ornamental design for a stand as shown and described.

JOHN B. HUE.
